Primary Examiner — Elizabeth J Oswecki(74) Attorney, Agent, or Firm — Bartholomew Law PC;
 Michael Bartholomew(57) CLAIM

The ornamental design for a piggy shaped coin bank as shown and described.

DESCRIPTION

FIG. 1 is a perspective view of a piggy shaped coin bank showing my new design;

FIG. 2 is a side view thereof;

FIG. 3 is an opposite side view thereof;

FIG. 4 is a top view thereof;

FIG. 5 is a bottom view thereof;

FIG. 6 is a front view thereof; and,

FIG. 7 is a back view thereof.

The broken lines shown in the drawings represent portions of the piggy shaped coin bank that form no part of the claimed design.

1 Claim, 7 Drawing Sheets(56)
